Pearl River, N. Y., a corporation of New
York

Application May 5, 1938, Serial No. 206,122

22 Claims. (Cl. 271—31)

This invention relates to a sheet feeder which is capable of forwarding a continuous underlapped series of individually registered sheets. The invention is an improvement or modification 5 of the invention described in my copending application Serial No. 138,119, now Patent No. 2,144,057 and its principal object is to provide a pickup device which will operate with certainty without the use of combing wheels, or 10 similar buckling devices, in conjunction with sheet registering means of the type described in said copending application.

The invention will be described in detail with reference to the accompanying drawings, where- 15 in—

Fig. 1 is an outline plan view of a sheet feeder, of which a separator embodying the present invention forms a part;

Fig. 2 is a side elevation of the separator and 20 forwarder mechanism;

Fig. 3 is a plan view of the same;

Fig. 4 is a vertical section looking forward on the line 4—4 of Fig. 3;

Fig. 5 is a front elevation of the separator and 25 forwarder;

Fig. 6 is a vertical section on the line 6—6 of Fig. 3, showing the separator mechanism in two positions;

Fig. 7 is a vertical section on the line 7—7 30 of Fig. 3, showing the separator mechanism in two other positions;

Fig. 8 is a simplified view showing two positions of the suction head;

Fig. 9 is a similar view showing the suction 35 head in two other positions;

Fig. 10 is a side elevation of the suction head;

Fig. 11 is a plan view thereof;

Fig. 12 is a detail plan view, with parts in section, of a modified form of suction cup spreader 40 mechanism;

Fig. 13 is a side elevation of the same mechanism;

Fig. 14 is a detail perspective view of a cam which forms part of the mechanism shown in 45 Figs. 12 and 13; and

Fig. 15 is a vertical section on the line 15—15 50 of Fig. 3.

In Fig. 1 is shown a sheet feeder comprising a table 10 onto which a fanned out bank of 55 sheets is conveyed over a roller 12 from an upper loader table (not shown) by conveyor bands 14. The paper is fed down through a reversing throat formed by the roller 12 and lower conveyor bands 16, thence out onto the table 10.

This arrangement is well known and does not require detailed description.

The construction of the sheet feeder shown in the present application follows in a general way the one shown in my Patent No. 2,144,057. 5 There are two separator heads A and B (head A only being selected for full illustration), mounted above the table 10 upon a carriage formed by a transverse pipe 18 mounted by riders 20 at its ends upon guides 22 fixed to the side frames 24 10 of the machine. The carriage can be made to travel longitudinally of the table 10 by means of a crank 26 on a shaft 28 (Fig. 2) to which are keyed gears 30 meshing with teeth 32 on guides 22. Each separator and feeder head is 15 mounted on the pipe 18 by a bracket 33, the body of which is in the form of a sleeve 34; and this sleeve is keyed to pipe 18 by a key 40 (Fig. 7) so as to be able to slide along the pipe without turning. The operative mechanism of each 20 separator and forwarder is mounted in a bracket 42 comprising side plates 43 and 45 joined by a rear plate 47 (Fig. 3). In the corners where the side plates are joined to the rear plate are two bores 44 (Fig. 6), in which are fixed tubes 25 46 and 48 mounted to slide vertically in ears 36 and 38 of bracket 33. Within the tubes are counterbalancing springs 50, the lower ends of which are hooked over pins 52 fixed to the tubes and the upper ends over pins 54 fixed in the ears 30 36 by set screws 56. The two tubes 46 and 48 are slotted at 58 to allow them to slide up and down past the pins 54. Upon a depending arm 60 of the bracket 42 is a roller 62 which rests 35 upon the bank of paper 64 with a weight equal to the weight of the separator head, minus the force of the counterbalancing springs 50. The separator heads can be raised from the bank of paper by a pedal 66 on a shaft 68 which is rock- 40 ably mounted in bearings 69 on brackets 33 and riders 20. The shaft 68 has fixed to it levers 70 carrying pivoted links 72 slotted at 74 to receive pins 76 on the brackets 42.

Each separator head has a suction cup 80 which picks up the top sheet of the bank near its 45 rear marginal portion and a forwarding suction cup 82 which takes the sheet from the cup 80 and moves it forward to the drop rollers. The suction cups 80, after picking up the rear margin of the sheet, move the sheet bodily rearward 50 into engagement with trip fingers 84, which form part of rear edge register devices arranged to terminate the rearward movement of the sheet in a definite position in which its rear edge is perpendicular to the longitudinal axis of the 55

feeder table. The forwarders thus engage each sheet at a definite distance from its rear edge and move it in correctly aligned position forward to the drop rolls.

- 5 The suction cup 80 forms part of a suction head comprising a casting 81 bored at 83 and 85 to provide communication between a nipple 86 upon which the suction cup 80 is mounted, and a nipple 87 to which is attached a suction hose 88.
- 10 The suction head normally rests upon the top sheet of the bank of paper 64 in a substantially horizontal position, the cup 80 and a pivot heel 89 being in contact with the paper. The suction head is operated in such a way, by mechanism
- 15 about to be described, that the rear margin of the sheet is bent up sharply from the bank, then, while the sheet is wound under its tilted rear margin, the latter is tipped back to a substantially horizontal position above the bank of paper,
- 20 so as to be in position to be moved rearwardly to the rear edge register devices. The suction head is connected to two lifting levers 90 and 92 by two links 94 and 96 respectively. The link 94 is pivotally connected to a stud 98 projecting
- 25 from an arm 99 of the casting 81. The link 96 is pivotally connected to the suction head by a pin 100 adjacent to pivot heel 89. The stud 98 and pin 100 are spaced apart horizontally, the former being located relatively close to the suction cup
- 30 80, while the latter is somewhat further from the suction cup and close to the top sheet of the bank of paper. The pin 100 and heel 89 are quite near to the suction cup 80, in order that the latter, when tilted around them, may bend up
- 35 the rear margin of the sheet sharply from the bank to effect a clean separation from the second sheet. The levers 90 and 92 are pivotally mounted at their right hand ends upon a shaft 102 fixed in bearings 104 and 106 extending upward from the side plates 43 and 45, respectively.
- 40 The lever 90 has a pin 108 rotatably supporting a roller 110 which rides upon a cam 112 fixed upon a shaft 114. The lever 92 has a pin 116 pivotally supporting a roller 118 which rides upon a cam
- 45 120 fixed to shaft 114. The levers 90 and 92 are pulled downward by springs 91 and 93 connected to hooks 95 and 97 on their respective ends, and to a pin 101 on a lever 140. The shaft 114 is mounted in bearings 122 and 124 in the side plates 43 and 45, respectively, and is driven by a telescoping shaft 126 connected by a universal joint 128 to a shaft 130 mounted in bearings 132 and 134 projecting from the side plate 45. A bevel gear 136 on shaft 130 meshes with a bevel gear 138 fixed to shaft 114. The drive of the telescoping shaft 126 is similar to that of the corresponding shaft in my Patent No. 2,144,057. The cams 112 and 120 cause vertical and tilting movements of the suction head, as will be described presently.

60 Horizontal movements of the suction head are derived from a swinging frame comprising the pendant lever 140 which is pivotally supported by a shaft 142 mounted between the side plates 43 and 45, a bell crank lever 144, 146 pivotally mounted on shaft 102, and a rack bar 148 pivotally connected to the lower ends of levers 140 and 144 by pins 141 and 145. The lever arm 146 carries a roller 149 riding upon a cam 150 fixed to shaft 116. A spring 152 is connected at one end to a pin 154 on lever 140 and at its other end to a pin 156 on a stationary plate 158 supported upon shafts 102 and 142. The spring 152 tends to swing the frame 140, 144, 148 to the right, holding the roller 149 against cam 150.

65 The lower end of lever 140 is connected by a link 160 to the pin 100 of suction head 80. The connection of link 160 to lever 140 is provided by a pin 162 on which the link can slide axially of the pin for a purpose to be described presently. It will be seen that movements imparted to the lever 146, 144 by cam 150 will be transmitted through rack bar 148 to lever 140, and through link 160 to the suction cup 80, moving the latter in a substantially horizontal direction.

70 There is a rear edge registering device on each separator head. Each comprises a paper guide for presenting the paper to the trip finger 84. The paper guide is formed by two plates, 164 and 166, mounted by a block 168 upon a downward projection 170 of plate 158. The front end of the plate 164 curves downward to a position close behind the rear edge of the top sheet, the bank of paper being moved forward in well-known manner, for instance by the bank feed mechanism described in my copending application Serial No. 172,728, now Patent No. 2,144,058 to keep the successive top sheets moving to a position just in front of the guide plate 164. The upper guide plate 166 extends forward for a considerable distance above the rear edge of the top sheet, so that the rear margin of the sheet being separated is always between the two guide plates 164 and 166. The guide plate 166 lies inside the trip finger 84 while the guide plate 164 is bifurcated at 172 and the trip finger extends downward between its forks. The trip finger 84 is fixed to a downwardly extending arm 175 of a hub 176 which is pivotally mounted upon a stud 178 projecting from the plate 158. A leftwardly extending arm 180 of hub 176 has fixed to it a pawl 181, the downwardly directed end of which is positioned above a series of teeth 182 of rack bar 148. The hub 176 is normally held by a spring 184 so that its lug 186 bears against a fixed pin 188 on plate 158. The tilting element comprising the trip finger 84, hub 176, and pawl 181 is adapted to be tipped by engagement of the rear edge of the rearwardly moving sheet with the trip finger 84, to throw the pawl 181 into engagement with teeth 182 and thereby stop the rearward movement of the rack bar 148 and parts connected to it.

75 Means are preferably provided to spread the two suction cups 80 apart as they raise the rear marginal portion of the sheet, in order to hold the sheet taut for better engagement by the forwarders. I have shown two different forms of mechanism for this purpose. The first form, shown particularly in Figs. 2-7, is designed to spread the suction cups by a positive cam action. On the pin 162 inside of the hub 190 of link 160 is rockably mounted a hub 192 to which is fixed a cam 194. The cam bears against the end of pin 141 and has connected to it by a pin 196 a link 198, the upper end of which is attached to the lever 92 by the same pin 200 which supports the link 94. The hubs 190 and 192 are pressed inward against the lower end of lever 140 by a spring 202, the outer end of which is confined by a washer 204 locked by a cotter pin 206. In the lower position of lever 92 the cam 194 permits the hub 192 to rest against the lever 140, but when the lever 92 is raised the cam 194 bears against pin 141 and presses its hub 192 outward on pin 162. This also moves the hub 190 outward, and, as both separator heads are operating simultaneously, the suction cups 80 are spread apart for a distance sufficient to taunt the rear margin of the sheet.

80 Another form of spreader is shown in Figs. 75

12-14, this form being designed to spread the suction cups by a yielding force and being therefore particularly suited to handle the more delicate kinds of paper. To the lower end of a pendant lever 140a is pivotally attached a rack bar 148a. This rack bar extends beyond the pin 141a which connects it to the lever 140a and has rigidly fixed to its extension a pin 210 bearing a rigid arm 212. This arm carries a stud 214 which 5 serves as the base point on which the spreading cam operates. The suction head casting 81 is connected by a link 160a to a pin 162a on the lower end of lever 140a, the pin and link being fixed together by a set screw 216. Between the 10 hub 190a of link 160a and the lower end of lever 140a is a cam hub 192a, which bears a cam 194a. The pin 162a is pushed by a spring 202a in a direction which tends to move the shaft and the parts connected thereto from the full line position 15 of Fig. 12 to the dash line position. This spring 202a is confined between an arm 218 fixed to the lower end of lever 140a and a washer 204a resting against a shoulder of the pin 162a. The link 198 is connected to cam 194a by a pin 25 196, so that when moved up by lever 92 (Fig. 6) the cam 194a moves from its full line position to its dash line position, permitting pin 162a to move under the influence of spring 202a. On the two separator heads the spreader mechanisms 30 are reversed in position and arranged so that the force of the springs 202a is in the direction tending to spread the suction cups 80 apart.

The forwarder mechanism is of the same type as the second embodiment described in my Patent No. 2,144,057. Upon a shaft 220 rotatably mounted in bearings 222 and 224 at the front ends of the side plates 43 and 45, respectively, is fixed a clamp 226. This clamp holds a telescoping suction feeder 228, which may be of the same design as the one shown in my aforesaid Patent No. 2,144,057. This suction feeder is supported in the clamp 226 by a tube 230 to which is attached a suction hose 232. Also fixed upon the shaft 220 is the hub 234 of a lever 236, the lower end of which is connected by a pin 238 to a pitman 240 (Fig. 3). This pitman carries a roller 242 which rides upon a cam 244 fixed to shaft 114. A spring 246 attached at one end to a pin 248 on plate 45 and at its other end to a pin 250 on lever 236 pulls the pitman 240 in the direction which holds its roller 242 against the cam 244. This mechanism imparts to the suction feeder 228 a simple rocking movement which is timed to move the sheet from the rear edge register devices to the drop rolls. A blow pipe 252 is mounted by a clamp 254 upon the side plate 43 and supplied with compressed air from a hose 256. The purpose of this blow pipe is to flutter the rear edge of the top sheet and to blow air under the same when it is tilted up. A hollow foot clamp 258 is mounted by a clamp 260 upon a pin 262 at one end of a lever 264. This lever is rockably mounted upon a shaft 266 carried in bearings 268, 269, and 270 of plates 43, 45, and 158, respectively. 55 The rear end of this lever carries a roller 272 which rides upon a cam 274 fixed to shaft 114, being held to the cam by a spring 276 stretched between a pin 278 on lever 264 and a pin 280 on the plate 158. The upper end of foot clamp 258 is connected to a compressed air hose 282. The upper end of clamp 260 is formed as a cam slot 284 which embraces a roller 286 rotatably mounted by a pin 288 upon plate 158. The mounting of the clamp foot 258 is such that under the 60 action of cam 274 it executes a combined upward

and tilting movement, the upper limit position of which is indicated by dash lines at 290 in Fig. 15.

The several suction and compressed air hoses lead back to a valve 300 (Fig. 1). The two forward nipples on each side of this valve, to which the hoses 88 and 232 are connected, are on the suction side of the valve. The hoses 256 and 282 are connected to pressure nipples on each side of the valve mechanism. Compressed air is supplied to the valve from a compressor (not shown) 10 by a pipe 302, and a pipe 304 connects the vacuum side of the valve with the intake of the compressor. The valve is rotated in synchronism with the separator heads by a telescoping shaft 306. 15

The operation of the device will now be described:

The bank of paper is fed forward by any suitable bank feeding means, so that the rear edge of the top sheet of the bank is just in front of the paper guide 164, and the suction cups 80 are normally resting upon the rear margin of the top sheet as shown in Figs. 6 and 8, position I. Through the valve 300 a vacuum is applied to the suction cups 80, so that they grip the top sheet and cams 214 kick the foot clamps up from the top sheet. Thereupon levers 92 are raised by cam 120, lifting links 94 and tilting the suction heads about the pivot heels 89 and pins 100. During this time compressed air is blown through nozzles 252 to flutter the rear margin of the top sheet. The foot clamps 258 quickly drop under the rear margin of the top sheet as it is being turned up by the suction cups and clamp down the second sheet. At this moment the valve 300 35 sends blasts of air through the foot clamps to assist the separation of the top sheet from the pile. The links 198 are lifted simultaneously with the links 94 to spread the suction cups 80 apart and tauten the rear margin of the top sheet. When the suction cups 80 approach position II in Figs. 6 and 8 the rear margin of the sheet is bent up sharply from the heels 89 and is definitely free from the second sheet. Now cams 112 begin to raise levers 90, which, through links 96, lift the pins 100 of the suction heads 40. At this time the upward movement of levers 92 is slowing down to a stop, so that the suction heads are tipped back to a substantially horizontal position as the pins 100 are raised. The lifting of 45 the pins 100 has the effect of straightening the toggles constituted by the suction heads and the links 160, which would move the suction cups rearward prematurely. To avoid this result the cams 150 are shaped to move levers 140 forward to take up the motion of the toggles 160, 81, in order that the suction cups 80 may remain approximately in the same fore and aft location as they are being tipped back to a horizontal position. Figs. 7 and 9 show in dotted lines the 50 position of the parts when the pins 100 have been raised to the limit of their vertical movement, this being noted as position III of the suction cups 80. There follows a rearward movement of the suction cups from position III to position IV, 55 under the force of springs 152 and control of cams 150. As the rear edge of the paper touches each trip finger 84 the corresponding pawl 181 is tipped down into engagement with the teeth 182 of the corresponding rack bar 148. This may occur at one side sooner than the other, if the rear edge of the sheet is not perpendicular to the longitudinal axis of the feeder table, but when both pawls 181 have engaged their rack bars the 60 sheet will be correctly registered. 75

The swinging motion of the forwarder cups 82 is timed so that they reach their rearmost position shortly after the separated sheet has been registered. At this moment suction is applied to 5 the cups 82, which dip down and grasp the tautened rear portion of the sheet. The suction is cut off from cups 80 at the same moment and the forward feed of the sheet is carried out by the forwarding cups 82. The cams 112 and 120 drop 10 the pickup suction head back onto the bank as soon as the rear edge of the previously separated sheet has passed the heels 89. The operation is then repeated, the sheets being separated and fed forward in such rapid succession that they 15 form a continuous stream of underlapped individually registered sheets.

In this art a distinction is frequently made between sheet feeders which take sheets from a vertical pile and those which take sheets from a 20 fanned out bank. The former are commonly called "pile feeders" and the latter "bank feeders." The present invention can be used for feeding from either arrangement of sheets and the term "pile" as used in the present specification and claims is not intended to denote a particular arrangement of sheets to be separated.

I claim:

1. In a device for separating sheets from the top of a pile one at a time, a plurality of registering devices spaced apart near the rear edge of the top sheet, a plurality of suction cups mounted near said edge at spaced points, each being mounted so as to tilt about a nearby center adjacent the rear of the top sheet, from a 30 horizontal position in which the suction cup rests upon the top sheet, to a sharply inclined position above the pile; means for tilting said suction cups about said centers to raise the rear margin of the top sheet at a sharp angle to the pile; means for then rocking said suction cups to an approximately horizontal position above the pile; means for winding the sheet; and means for moving said suction cups approximately horizontally to bring the rear edge of the sheet to 40 said registering devices.

2. In a device for separating sheets from the top of a pile one at a time; a plurality of registering devices near one edge of the top sheet; a plurality of suction cups located near said edge; a plurality of supports, each suction cup being mounted on one of said supports for pivotal movement about a nearby center adjacent the top sheet; means for tilting said suction cups about said centers from a position against said 50 top sheet to a sharply inclined position above the pile; means for lifting said supports while holding said suction cups at approximately the same elevation, thereby rocking the suction cups to a substantially horizontal position above the pile; means for winding the sheet; and means for moving said suction cups approximately horizontally to bring the edge of the sheet to said registering devices.

3. In a device for separating sheets from the top of a pile one at a time; a plurality of registering devices near one edge of the top sheet; a plurality of suction heads each bearing a suction cup normally located near said edge in a substantially horizontal position against the top 60 sheet; a pair of lifting devices for each suction head, the individual lifting devices of each pair being pivotally connected to the appurtenant suction head at two horizontally spaced points, means for operating the individual lifting devices of each pair successively to first tilt said

suction heads about one of said pivot points, thereby moving said suction cups into a sharply inclined position above the pile, and to then tilt said suction heads about said other pivot point to move said suction cups to a horizontal position above the pile; means for winding the top sheet; and means for bodily moving said suction heads horizontally to bring the edge of the paper to said registering devices.

4. In a device for separating sheets from the top of a pile one at a time; a plurality of registering devices near one edge of the top sheet; a plurality of suction heads each bearing a suction cup normally located near said edge in a substantially horizontal position against the top sheet; a pair of lifting devices for each suction head, the individual lifting devices of each pair being pivotally connected to the appurtenant suction head at two horizontally spaced points, one of which is adjacent the vertical axis of the suction cup, while the other is further from said vertical axis and close to the top sheet of the pile; means for operating the individual lifting devices of each pair successively to first tilt said suction heads about said second-mentioned pivot point to raise said suction cups to a sharply inclined position above the pile, then to tilt said suction heads about said first-mentioned pivot point to move said suction cups to a substantially horizontal position above the pile; means for winding the sheet; and means for bodily moving said suction heads horizontally to bring the edge of the paper to said registering devices.

5. In a device for separating sheets from the top of a pile one at a time; two registering devices located near the rear edge of the top sheet at widely spaced points; two pickup devices, each comprising a suction cup located near said rear edge, a support upon which said suction cup is mounted for pivotal movement about a nearby center adjacent the top sheet, means for tilting the suction cup about said center from a position against the top sheet to a sharply inclined position above the pile, and means for lifting said support while holding said suction cup at approximately the same elevation to rock the suction cup to a substantially horizontal position; means for winding the sheet; means for moving said suction cups approximately horizontally to bring the rear edge of the sheet to said registering devices; and means controlled by each registering device to interrupt the horizontal movement of the appurtenant suction cup.

6. In a device for separating sheets from the top of a pile one at a time; two registering devices located near the rear edge of the top sheet at widely spaced points; two pickup devices, each comprising a suction cup located near said rear edge, a support upon which said suction cup is mounted for pivotal movement about a center adjacent the top sheet and near the suction cup, means for tilting the suction cup about said center from a position against the top sheet to a sharply inclined position above the pile, and means for lifting said support while holding said suction cup in approximately the same elevation to rock the suction cup to a substantially horizontal position; means for winding the sheet; means for moving said suction cups approximately horizontally to bring the rear edge of the sheet to said registering devices; means controlled by each registering device to interrupt the horizontal movement of the appurtenant suction cup; and means operable to spread said supports

apart when the suction cups have been raised from the pile.

7. In a device for separating sheets from the top of a pile one at a time; two registering devices located near the rear edge of the top sheet at widely spaced points; two pickup devices, each comprising a suction cup located near said rear edge, a support upon which said suction cup is mounted for pivotal movement about a center adjacent the top sheet and near the suction cup, means for tilting the suction cup about said center from a position against the top sheet to a sharply inclined position above the pile, and means for lifting said support while holding said suction cup in approximately the same elevation to rock the suction cup to a substantially horizontal position; means for winding the sheet; means for moving said suction cups approximately horizontally to bring the rear edge of the sheet to said registering devices; means controlled by each registering device to interrupt the horizontal movement of the appurtenant suction cup; and means operable simultaneously with said tilting means to spread said supports apart as the suction cups are being raised from the pile.

8. In a device for separating sheets from the top of a pile one at a time; two registering devices near the rear edge of the top sheet, each comprising guide means for the rear edge of the sheet and a trip finger intersecting said guide means; a pair of pickup devices located at widely spaced points above the rear edge portion of the top sheet, each comprising a suction cup, a support upon which the suction cup is mounted for pivotal movement about a nearby center adjacent the top sheet, means for tilting the suction cup about said center from a position against the top sheet to a sharply inclined position above the pile, and means for lifting the support while holding the suction cup at approximately the same elevation to rock the suction cup to a substantially horizontal position; means for winding the sheet under its raised rear edge; means for moving said suction cups approximately horizontally to bring the rear edge of the sheet into engagement with said trip fingers, comprising rack bars respectively connected to said suction cups; and pawls movable by said trip fingers to engage the respective rack bars to stop each suction cup independently of the other.

9. In a device for separating sheets from the top of a pile one at a time; two registering devices located near the rear edge of the top sheet; a pair of suction heads each bearing a suction cup normally located near said rear edge in a substantially horizontal position against the top sheet; means for independently moving said suction heads, each comprising two lifting devices pivotally connected to their suction heads at two horizontally spaced points, means for operating the two lifting devices of each head successively to first tilt said suction head about one of said pivot points, thereby moving the suction cup into a sharply inclined position above the pile, and then to tilt said suction head about said other pivot point to move the suction cup to a horizontal position above the pile; means for winding the sheet; cam means operated by said first-mentioned lifting devices for effecting a transverse spreading movement of said suction heads; and means for bodily moving said suction heads horizontally to bring the rear edge of the paper to said registering devices.

10. In a device for separating sheets from the top of a pile one at a time, a registering device

near one edge of the top sheet, a pendant lever above the rear portion of the top sheet, a substantially horizontal rack bar pivoted to said lever, a pawl controlled by said registering device adapted to be engaged with the teeth of said rack bar to limit its horizontal movement, a suction head mounted on the foot of said lever by a link permitting bodily vertical movement and tilting movement of the suction head, a suction cup on said suction head normally in a horizontal position against the rear portion of the top sheet, means for first tilting said suction head to bend up the rear edge of the top sheet sharply from the pile, means for winding the top sheet under its raised rear edge, then raising the suction head bodily from the pile while tilting it back to restore the rear edge of the top sheet to a horizontal position, and means for moving said lever rearwardly to bring the rear edge of the sheet to said registering device, thereby engaging said pawl with said rack bar and terminating the rearward movement of the sheet.

11. In a device for separating sheets from the top of a pile one at a time, a suction head, an operating member therefor, a link articulately connecting said suction head to said operating member, the connection between said link and said operating member being a pivot permitting rocking movement of the link about a horizontal axis and axial sliding movement on said pivot, actuating means for imparting vertical and tilting movements to said suction head, and means for sliding said link on said pivot.

12. In a device for separating sheets from the top of a pile one at a time, a suction head, an operating member therefor, a link articulately connecting said suction head to said operating member, the connection between said link and said operating member being a pivot permitting rocking movement of the link about a horizontal axis and axial sliding movement on said pivot, actuating means for imparting vertical and tilting movements to said suction head, a cam rockably mounted on said pivot and operative to slide said link axially on said pivot, and a connection whereby said cam is operated by said actuating means.

13. In a device for separating sheets from the top of a pile one at a time, two suction heads, two operating members therefor, links articulately connecting said suction heads respectively to said operating members, the connections between said links and said operating members each being a pivot permitting rocking movement of the link about a horizontal axis and axial sliding movement on said pivot, actuating means for imparting vertical and tilting movements to said suction head, springs tending to slide said links outwardly from each other on said pivots, and cams operated by said actuating means to slide said links toward each other on said pivots.

14. The method of separating a single sheet from the top of a pile of sheets, which comprises engaging the top sheet near its rear edge by two widely spaced suction cups, tilting up said suction cups to draw the rear edge portion of the top sheet up from the pile at a sharp angle, then tilting the suction cups back to a substantially horizontal position while holding them above the pile, and then drawing the sheet rearwardly to registering devices while winding the sheet below its raised rear edge.

15. In a sheet feeding mechanism, suction sheet separators arranged to engage opposite rear portions of the sheet, means for tilting the sep-

5 arators to bend up the rear edge portion of the sheet along the length thereof, means arranged rearwardly of the sheet for registering it and controlling rearward movement of the separators, 10 and means for raising the separators and moving them rearwardly to lift the sheet and move it rearwardly into engagement with said registering and controlling means.

16. In a sheet feeding mechanism, suction sheet 10 separators arranged to engage opposite rear portions of the sheet, means for tilting the separators to bend up the rear edge portion of the sheet along the length thereof, means arranged rearwardly of the sheet for registering it and 15 controlling rearward movement of the separators, means for raising the separators and moving them rearwardly to lift the sheet and move it rearwardly into engagement with said registering and controlling means, and suction means for engaging 20 the raised rearwardly moved and registered sheet at the rear thereof and for moving said sheet forwardly.

17. In a sheet feeding mechanism, suction sheet separators arranged to engage opposite rear portions of the sheet, means arranged rearwardly of the sheet for registering it and controlling rearward movement of the separators, and means for lifting the separators, imparting relative lateral movement thereto, and moving 30 them rearwardly, to lift the sheet, stretch it transversely thereof, and move said sheet rearwardly into engagement with said registering and controlling means.

18. In a sheet feeding mechanism, suction sheet separators arranged to engage opposite rear portions of the sheet, means arranged rearwardly of the sheet for registering it and controlling rearward movement of the separators, means for lifting the separators, imparting relative lateral movement thereto, and moving them 40 rearwardly, to lift the sheet, stretch it transversely thereof, and move said sheet rearwardly into engagement with said registering and controlling means, and suction means for engaging the raised, stretched, rearwardly moved and registered sheet at the rear thereof and for moving said sheet forwardly.

19. The method of feeding sheets from a supply thereof to a machine for acting on the sheets, 50 which comprises engaging each sheet by suction at the rear and stretching the sheet transversely thereof while it is so engaged, moving the sheet rearwardly through suction engagement therewith and registering the sheet with respect to said machine through rearward movement of said sheet, and moving the registered sheet forwardly relative to said supply and said machine.

20. The method of feeding sheets from a supply thereof to a machine for acting on the sheets, which comprises engaging each sheet by 60 suction at the rear and stretching the sheet

transversely thereof while it is so engaged, moving the sheet rearwardly through suction engagement therewith and registering the sheet with respect to said machine through rearward movement of said sheet, engaging the registered sheet at the rear thereof by suction and moving said sheet forwardly over said supply into lapped relation with a previously fed sheet, and conveying a stream of sheets so registered, fed and lapped from the supply to said machine. 10

21. In a continuous stream feeder having means for feeding a bank of fanned out sheets, the combination of laterally spaced means engageable with the rear edge of the leading sheet 15 of the bank for registering or squaring up that sheet with respect to the machine to which it is fed, and mechanism for separating the leading sheet of the bank therefrom and forwarding said sheet under and in lapped relation with a sheet previously separated and forwarded relative to 20 the bank, said sheet separating and forwarding mechanism comprising laterally spaced suction type sheet separating members arranged to act on the rear edge portion of the leading sheet of the bank and adapted to stretch said rear edge 25 portion of said sheet and bring it into position for action thereon of said sheet registering or squaring up means, and sheet forwarding means comprising laterally spaced sheet engaging devices arranged to act on the rear of said leading 30 sheet of the bank when the rear edge portion of said sheet has been stretched and positioned as aforesaid.

22. In a continuous stream feeder having means for feeding a bank of fanned out sheets, 35 the combination of means engageable with the rear edge of the leading sheet of the bank for registering or squaring up that sheet with respect to the machine to which it is fed, and mechanism for separating the leading sheet from the bank 40 and forwarding said sheet under and in lapped relation with a sheet previously separated and forwarded relative to the bank, said sheet separating and forwarding mechanism comprising movable suction type sheet separating members 45 arranged in spaced relation transversely of the feeder to act on the rear edge portion of the leading sheet of the bank, sheet forwarding and controlling means comprising devices engageable with the rear edge portion of said sheet, and 50 means for imparting sheet engaging, stretching and positioning movements to said sheet separating members whereby they engage the rear edge portion of the leading sheet, stretch it transversely of the feeder, and bring said rear edge 55 portion into position for the action thereon of said sheet registering or squaring means and said devices of said sheet forwarding and controlling means.

HENNING HALLSTREAM. 60
